UNITED STATES PATENT OFFICE.

EDWARD B. LEWIS, OF PACIFIC GROVE, CALIFORNIA.

DESIGN FOR A LAMP-SHADE.

No. 38,264.

Specification for Design.

Patented Oct. 2, 1906.

Application filed August 27, 1906. Serial No. 332,271. Term of patent 14 years.

To all whom it may concern:

Be it known that I, EDWARD B. LEWIS, a citizen of the United States, and a resident of Pacific Grove, county of Monterey, and State of California, have invented a new, original, and ornamental Design for Lamp-Shades, of which the following is a specification, reference being had to the accompanying drawings, forming part thereof.

plan view, of a lamp-shade, showing my new design.

I claim—

The ornamental design for a lamp-shade, as shown.

EDWARD B. LEWIS.
